UNITED STATES PATENT OFFICE.

EDWARD STOUT, OF BRIGHTON, IOWA.

HOIST.

1,276,281.

Specification of Letters Patent. Patented Aug. 20, 1918.

Application filed December 27, 1917. Serial No. 209,063.

To all whom it may concern:

Be it known that I, EDWARD STOUT, a citizen of the United States, residing at Brighton, in the county of Washington and State of Iowa, have invented certain new and useful Improvements in Hoists; and I do declare the following to be a full, clear, and exact description of the invention, such as will enable others skilled in the art to 10 which it appertains to make and use the same.

My invention has for its object to provide a simple and inexpensive yet a highly efficient and durable machine for operating the 15 two cables or ropes used upon hay forks in stowing the hay into the mow, the construction being such as to require one person only to unload the hay from the wagon and deposit it in the mow.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a side elevation of the machine;

Fig. 2 is a top plan view;

Fig. 3 is a central longitudinal section on the plane of the line 3—3 of Fig. 2; and

Fig. 4 is a perspective view showing more particularly one of the friction brakes for 35 checking the unwinding movement of the two drums.

In the drawings above briefly described, the numeral 1 designates a suitably mounted frame including a base 2, four vertical posts 40 3, and a pair of parallel horizontal bars 4 extending longitudinally of the frame and supported at their ends by said posts. A drive shaft 5 extends between the two bars 4 and passes through openings therein, one 45 end of said shaft having a pulley or the like 6 by means of which it may be driven, while a friction driving wheel 7 is secured on the other end of said shaft. Parallel links 8 are pivoted to and rise from the bars 4, the 50 upper ends of said links being pivoted to a pair of longitudinal bars 9 which carry a main winding drum 10 and an auxiliary drum 10^a, said drum 10 having a relatively large friction wheel 11 for contact with the 55 driving wheel 7, while drum 10^a is equipped

with a somewhat smaller friction wheel 11^a for engagement with said driving wheel.

A main pull rope 12 is wound on the drum 10 and leads to the hay fork in the usual manner, for raising and lowering this 60 fork and pulling its carriage along the common overhead track. An auxiliary pull rope or trip cable 12^a is wound upon drum 10^a and this cable serves to trip the fork after it has been drawn to the desired point, and 65 then acts to return the fork to the outer end of the track. When either drum is in operation to wind its respective rope, the other drum is free to unwind, but in order to prevent possible tangling of the ropes, a pair 70 of friction brake shoes 13 are provided, these shoes coöperating with the friction wheels 11 and 11^a and being carried on the upper ends of vertical arms 14 which are pivoted to longitudinal bars 15, said last 75 named bars having their ends bent upwardly to form hangers 15' which are secured to the bars 9. Links 16 connect the upper ends of the arms 14 with the arms 17 of arched brake operating members 18, the crown bars 80 of said members 18 being preferably formed of rollers 19 for engagement with the cables 12 and 12^a. By this means, the brake of either drum will be applied when the cable is being unwound from such drum, to prevent the cable from paying out too rapidly and possibly becoming tangled, springs 20 being connected to the arms 17 for so applying the brakes the moment the cable is slack. As soon as the cable is placed under load, 85 however, the member 18 is so moved as to release the brake to permit winding of said cable as will be clear from the drawings.

Coiled springs 21 connect one end of the bars 9 with the posts 3 at one end of the 95 frame 1, for so moving said bars as to bring the friction wheel 11^a into contact with the driving wheel 7, whereby to rotate the drum 10^a to wind its cable at 12^a. For shifting the bars 9 in the opposite direction 100 to operatively engage the friction wheel 11 with the driving wheel 7, a lever 22 is provided, said lever being operatively connected with the bars 9 by a rock shaft 23 upon which said lever is mounted, crank arms 24 105 extending from said rock shaft, and links 25 pivoted to said crank arms and to the bars 9. An operating rope or the like 26 extends from the upper end of lever 22 and is adapted to be actuated by a person 110

upon the load of hay, whereby the movement of the fork may be controlled as required.

For holding the lever 22 and consequently the bars 9 in a neutral position so that 5 neither drum will be rotated, a sector 27 and a spring-pressed dog 28 are provided, said dog being carried by the lever and said sector having a notch formed with an abrupt wall 29 and with an inclined wall 30 which 10 merges into its bottom. When dog 28 slowly approaches the notch, it drops into the same and its end 28' abuts the wall 29 and thus holds the lever in a neutral position, but when a quick pull is exerted upon 15 the rope 26, and this rope is then quickly released, the dog 28 is raised from the notch by the inclined wall 30 thereof and the action of the springs 21 then moves lever 22 so quickly as to cause the dog to jump 20 the notch, thus permitting said springs to move the bars 9 to position the wheel 11^a against the driving wheel 7. The end 28' of the dog 28 is beveled and when moving rapidly it will not lodge against the wall 29. 25 The device is installed at any suitable point and the ropes or cables 12 and 12^a of the hay fork are secured to their respective drums. Shaft 5 may now be driven by any suitable means and the control cable 26 is 30 positioned within easy reach of the driver of the hay wagon. By operating this cable in the proper manner, the fork may be lowered and slow release of the cable will then cause the lever 22 to stop at a neutral position, due to the coaction of the dog 28 with 35 the notch of the sector 27. The fork may now be forced into the hay and cable 26 is then pulled so that the bars 9 are moved to engage the friction wheel 11 of the main drum 40 10 with the driven friction wheel 7, the result being that the main rope 12 is brought into play to raise the loaded fork and draw it along the track to the required point, placing of this cable under load serving to automatically 45 release the braking means of the drum 10 as will be clear from Figs. 1 and 3. At the same time, however, since the cable 12^a is slackened, the braking means of drum 10^a will be automatically applied to prevent 50 this cable from unwinding too rapidly. When the loaded fork has reached the required point, the cable 26 is quickly released with the result that the springs 21 shift the bars 9 to engage the friction wheel 11^a with 55 the wheel 7, at the same time releasing the brake of drum 10^a and applying that of drum 10. The trip cable 12^a is now wound and the main cable 12 paid out so that the load is dumped and the fork returned to the 60 wagon. Upon release of cable 26 as set forth, the movement of lever 22 under action of the spring 21 is so rapid, as to cause the dog 28 to jump the notch of the sector 27.

From the foregoing, taken in connection 65 with the accompanying drawings, it will be

obvious that I have provided a simple and inexpensive machine for the purpose set forth, yet one which will be highly efficient and will require the attention of only one person. Since probably the best results are obtained from the several details shown and described, these details are preferably employed, but I wish it understood that within the scope of the invention as claimed, numerous minor changes may well be made. 75

I claim:

1. A machine of the class described comprising a main drum and a main pull rope wound thereon, an auxiliary drum and an auxiliary pull rope secured thereto, means 80 for driving either drum and simultaneously releasing the other drum to permit its rope to unwind, controlling means for said driving means including an operating member leading to a point remote from the machine, independent self-applied braking means for the two drums, and means operated by tightening of either rope when placed under load for releasing the braking means of its respective drum. 90

2. A machine of the class described comprising a pair of parallel horizontal supporting bars, a drive shaft extending between said bars and having on one end a friction driving wheel, a pair of additional bars spaced vertically from said supporting bars, parallel links connecting the two pairs of bars and pivoted to both, a pair of winding drums extending between said additional bars on opposite sides of said drive shaft and having friction wheels for contact with said friction driving wheel, spring means for moving said additional bars in one direction to engage the friction wheel of one drum with said driving wheel, and manually operated means for moving said additional bars in the other direction to position the friction wheel of the other drum against said drive wheel. 95

3. A machine of the class described comprising a pair of parallel winding drums each having a friction wheel, ropes wound on said drums, a friction driving wheel between said first named wheels, carrying means for said drums, means for shifting said carrying means to engage the friction wheel of either drum with said driving wheel, a pair of bars spaced from and secured to said carrying means, arms pivoted to said bars and having brake shoes for engagement with the friction wheels of said drums, arched brake operating members having the free ends of their arms pivoted to said carrying means, links connecting said first named arms and the arms of said arched members, and springs for moving said members to apply said brake shoes, the crown bars of said arched members being disposed for engagement with the ropes of said drums to hold the brake shoes of either 110 115 120 125 130

drum released when the rope of such drum is under load.

4. A machine of the class described, comprising a pair of parallel winding drums each having at one end a friction wheel, a friction driving wheel between said first named wheels, carrying means for said drums, spring means for moving said carrying means in one direction to engage the friction wheel of one drum with said driving wheel, a lever operatively connected with said carrying means for moving the latter in the opposite direction to engage the friction wheel of the other drum with said driving wheel, a sector adjacent said lever and

having a notch formed with an abrupt wall and an inclined wall, a spring pressed dog on said lever adapted to engage said abrupt wall to hold said carrying means in a neutral position against the tension of said 20 spring means, and an operating member connected to said lever and extending to a remote point.

In testimony whereof I have hereunto set my hand in the presence of two subscribing 25 witnesses.

EDWARD STOUT.
